UNITED STATES PATENT OFFICE.

CHARLES M. GREY, OF EAST ORANGE, NEW JERSEY.

DIE-CASTING APPARATUS.

Application filed April 7, 1919. Serial No. 288,082.

To all whom it may concern:

Be it known that I, CHARLES M. GREY, a citizen of the United States, residing at East Orange, county of Essex, and State of New Jersey, have invented a certain new and useful Die-Casting Apparatus, of which the following is a specification.

This invention is a die casting apparatus, and, speaking generally, the functional aims of the invention are to simplify the mechanism employed, render the same more automatic, and, otherwise increase its efficiency. More specifically, among the objects of the invention, though not the exclusive ones, may be mentioned the following.

The general arrangement of the several main working parts of the machine in such manner as to enable the same to be manipulated with less operators than are ordinarily required; to minimize the number of operations required in completing the cycle necessary to produce a given casting, thereby materially increasing the output or production of the machine; to so position and arrange the several parts of the machine as to materially diminish the liability of accident to an operator; to so co-ordinate the operation of the different mechanisms as to render such operations simultaneous and capable of manipulation through a common power mechanism; to provide the machine with a new type of sprue mechanism so arranged as to form a conduit for the metal from the pressure pot to the die; to provide mechanism for the breaking or disrupting of the sprue prior to the opening of the die, thereby obviating any strain on the casting incident to the breaking off of the sprue; to operate the several parts of the working mechanism in substantial synchronism, and without the necessity of any nicety of mechanical adjustment between the parts; to provide especially efficient cooling means for the plate which supports the sprue side of the die; to provide means for guiding the nozzle of the pressure pot into correct operative position for feeding metal to the die; to provide means whereby the main operating mechanisms are actuated pneumatically; and to so arrange the operating mechanisms that they are positioned rearwardly of, or at the opposite side, of the fixed die supporting plate from the side thereof which supports the die, thereby rendering the die more accessible and permit-

ting of the employment of dies of widely varying sizes.

Features of the invention other than those specified will be apparent from the hereinafter detailed description taken in conjunction with the accompanying drawings.

In the accompanying drawings I have illustrated different practical embodiments of the invention, but the constructions therein shown are to be understood as illustrative only, and not as defining the limits of the invention.

Figure 1 is a side elevation of a machine embodying the present invention.

Figure 2 is a plan view of the machine.

Figure 3 is a central vertical section through the machine longitudinally.

Figure 4 is a horizontal longitudinal section on a line 4—4 of Figure 1.

Figure 5 is a section on the line 5—5 Figure 3.

Figure 6 is a section on the line 6—6 Figure 3.

Figure 7 is a section on the line 7—7 Figure 2.

Figures 8 and 9 are central vertical sections taken longitudinally of the machine illustrating the central portion thereof, Figure 8 showing the parts in casting position and Figure 9 illustrating the same parts in retracted positions.

Figure 10 is a side elevation of a fragment of the machine showing certain mechanism for operating the pressure pot.

Figure 11 is a section on the line 11—11 Figure 10.

Figures 12 and 13 are face views of baffle plates positioned adjacent the air inlet of the pressure pot.

Figure 14 is a section on the line 14—14 Figure 15, and,

Figure 15 is a central section of the nozzle end of the pressure pot, showing the manner in which said nozzle end co-operates with the sprue die section through an intermediate member supported by the die carrying plate.

Die castings are produced in metal dies usually consisting of two sections which are capable of being separated for the purpose of removing the casting therefrom. Generally, the sprue is so arranged that its axis forms an angle of 90 degrees with the abutting faces of the die sections, which are forced together preliminarily to the casting

operation. The gate or sprue forming passage is generally located in one of the two main sections of the die, and suitable ejector mechanism is usually located in the other 5 section of said die.

In carrying out the present invention, these two sections of the die are supported on separate plates between which relative movement may be effected for the purpose 10 of opening and closing the die, and, in order that the following description of the machine may be clarified, I will hereinafter term that section of the die with which the sprue is associated, "the sprue-die section", 15 and the plate which carries said section, "the sprue-die supporting plate". Similarly, the die section which embodies the ejector mechanism will be hereinafter termed "the ejector-die section", and the plate which supports it, "the ejector-die supporting plate". 20

In the accompanying drawings, 1 designates the base of the machine, on the opposite ends of which base are mounted upright frames 2 and 3. The frames 2 and 3 are 25 securely bolted to the base and are held in spaced relation longitudinally of the machine by hollow tubular spacers 4. On the outer face of the frame 3 is mounted a plate 5, fixed to the frame, as clearly shown in 30 Figure 5, by means of bolts 6, which extend through elongated slots in the frame 3 and in ears formed on the plate 5. Vertical adjustment of the plate 5 may be had through the threaded adjusting bolts 7 while lateral 35 adjustment of said plate may be had through the adjusting bolt 8, the slots through which the bolts 6 pass serving to allow of such adjustment.

The plate 5 constitutes the sprue-die supporting plate. This sprue-die supporting plate, which, manifestly, also constitutes a gate member is water cooled by water passing through the connections 17 and 18, in order to keep the die at a working temperature 45 and also to keep the sprue channel at a proper temperature in the event that the intermediate water jacketed member 59, hereinafter described, is not employed. While efforts have been made along these 50 lines, a plate of the general type shown has pronounced advantages over former types. The sprue-die is carried by plate 5 and is designated in the drawings by the reference numeral 9. The sprue-die 9 is secured to the 55 plate 5 by means of clamps 10 which engage with die 9 and are rigidly clamped in position by bolts 11, as shown in Figure 3. The plate 5 is slotted as at 12 to allow of the passage of the bolts 11 through said plate, 60 and said bolts may be passed through any of said slots to secure the die to the plate, the particular slot through which the bolts pass depending upon the size of the die, so that a large variety of die sizes are applicable 65 for co-operation with the plate 5.

Mounted on the base 1 and between the frames 2 and 3 is a source of molten metal supply 14 which is contained within a crucible 15 forming part of a furnace 16 supported on the base 1. In this molten metal supply is supported, in a manner to be described later, a pressure pot from which the metal is ejected into the die by means of fluid pressure in the form of compressed gas or air. 70

The ejector-die section 19 has associated therewith any desired form of the usual ejector mechanism 20, and is mounted on, and carried by, an ejector box 25' which ejector box is fastened to and forms part of the ejector die section, the whole being attached to the ejector die supporting plate 25, which is mounted on, and supported by, four rods 21, which extend longitudinally 85 of the machine for substantially its entire length and pass through the hollow spacers 4. By mounting the ejector-die supporting plate 25 in the manner described, the ejector-die 19 is supported for movement toward and away from the sprue-die 9, for the purpose of opening and closing the die. The plate 25 is provided with slots corresponding to the slots 12 of the plate 5, and for the 90 same purpose.

The invention is not restricted to any particular type of pressure pot or its mounting or operating means, as the operating means would vary with tilting pots over that employed for those of the non-tilting type. However, for purposes of illustration a pot 100 of the non-tilting type is shown and suitable operating means is illustrated to actuate the same.

Extending longitudinally of the machine between the frames 2 and 3, and at either side thereof, are a pair of guides 22 on which are slidably mounted two hangers 23 and 24, best shown in Figures 6, 8 and 9. On the hanger 23 is supported a pressure pot 26. The hanger 23 has a depending 105 portion which is pivotally secured to the pressure pot by the pin 27, while pivotal movement of the pot on this pin is controlled by a threaded adjusting stem 28, pivoted to the pot at 29, and extending upwardly through a transverse portion 30 of the hanger 23. Nuts 31 are associated with the threaded stem 28, and by their manipulation, the pressure pot may be pivotally adjusted on the pin 27 to bring the nozzle 32 110 of the pressure pot into alignment with the inlet channel 33 of the sprue-die section. The pot and pool 14 are so associated with each other and with the die, that the pot is at all times partially submerged in the 115 molten metal pool 14, as shown in Figure 8, and 9, but, through the mounting of the pot on the hanger 23, said pot is adapted for 120 sliding movement on the guides 22 from the casting position of Figure 8, wherein the 125 casting position of Figure 8, wherein the 130

pot is in casting relation to the die, to the position of Figure 9, wherein it is shown as in retracted filling position, and vice versa. Suitable means may be provided for directly operating upon the hanger 23 to so move the pot, but, in the preferred embodiment of the invention, this movement is accomplished through intermediate means in the form of the hanger 24, which, as already described, is also slidably mounted on the guides 22.

It will be noted from the drawings, that those portions of the brackets which directly engage with the guides 22 are in interfering relation, one of the guide engaging bosses of hanger 24 occupying a position between the guide engaging members of the hanger 23, but not entirely filling the intermediate space. This construction allows of sliding movement of both hangers on the guides, and also permits of partial movement of one hanger without effecting the movement of the other, so that there may be said to be, in effect, lost motion between said hangers which has a particular advantage hereinafter more fully set forth.

As stated, the hanger 23 serves as a means for sliding the pot, and is, in turn, slid back and forth on the guides 22 by a pair of racks 35 which are connected through adjustable turnbuckles 36 to trunnions 34 projecting laterally from the hanger 24, as shown in Figures 10 and 11. The racks 35 are operated from the same source of power as are the rods 21, and in the preferred embodiment of this invention, the prime mover consists in pneumatic means.

Superimposed on the frame 2 with their axes extending transversely of the machine are a pair of cylinders 37, having pistons 38 and 39, one of which is associated with each cylinder. The pistons 38 and 39 are rigidly connected to one another by an intermediate rack 40, and are so associated that when one piston is in fully advanced position, the other is in fully retracted position, and vice versa. Compressed air is alternately introduced back of the piston 38 through an inlet 41, and back of the piston 39 through an inlet 42, said compressed air preferably being controlled from a suitable valve (not shown) to alternately move the pistons in opposite directions. Through this operation of the pistons the rack 40 is reciprocated and this rack forms the prime mover of the machine.

Mounted in upstanding relation in the frame 2 is a crank shaft 42 provided with a crank 43, and on this crank shaft is fixed a gear 44 meshing with the rack 40 so that the rack, when reciprocated, serves to oscillate the crank shaft 42. Associated with the crank 43 is a connecting rod 45, the opposite end of which is pivotally secured to a piston 46 which is in turn pivoted to the

center of a head 47. (See Figures 3 and 4.) The opposite ends of the head are provided with apertures through which extend the stems 48 of a pair of racks 49. The stems 48 are threaded at their ends to receive adjusting bolts, and between the adjusting bolts and the forward portion of the head 47 are interposed coil springs 50. The racks 49 mesh with gears 51, mounted on a shaft 52, extending transversely of the frame and journalled for rotation in brackets 53 carried by the frame 2. (See Figures 1, 4, 7, 10 and 11.) Also fixed on the shaft 52 are additional gears 54 with which the racks 35, which control the movement of the pressure pot, co-operate.

In the commercial adaptation of the invention, the springs 50 form an important part since the seating of the nozzle of the pressure pot in the intermediate member is accomplished by the head 47, through the compression of these springs, so that said pot is virtually held to its seat by the compression of the said springs which in turn are placed under compression by said head 47, operated upon by the connecting rod as described. Because of the fact that the pressure pot is yieldably held to its seat, nicety of adjustment in the operating parts of the machine is rendered unnecessary. If no yielding connections were employed between the prime mover, the pressure pot, and the movable die member, a great nicety of adjustment would be required so that the pressure pot would come into correct casting position at the very instant the die was closed, or vice versa, and if this adjustment were disturbed through wear, or for other reasons, correct casting co-action could not be obtained. Through the employment of the yielding connections, however, the pressure pot is normally forced to its seat slightly before the guide is fully closed, and the slight subsequent movement required to bring the die into fully closed position is taken up by the springs which merely serve to force the pressure pot more tightly to its seat.

As the crank shaft 42 is operated by the rack 40, the connecting rod 45 reciprocates the head 47 which results in reciprocation of the racks 39 and rotation of the shaft 52. The rotation of shaft 52 operates the racks 35 through the gears 54 and shifts hanger 24 longitudinally of the guides 22. The hanger 24 carries a transverse bar 55 which, as the hanger moves forwardly, engages with the nozzle end of the pressure pot 26, after the manner shown in Figure 8, and through said rod 55, which is squared to better engage the pot, the pot is slid forwardly on the guides 22 into casting position. However, when the hanger 24 is retracted, i. e., moved in a retrograde direction, the bar 55 is disengaged from the pot, and the

1
hanger rides idly on the guides 22 until the guide engaging members of said hanger come in engagement with the forward guide engaging members of the hanger 23, as shown in Figures 9 and 10, whereupon further movement of the hanger 24 causes the hanger 23 to be slid back along the guides 22 carrying therewith the pressure pot 26.

10 The object of the double hanger is as follows. It is desirable that the pressure which locks the pressure pot in its ejecting position be applied so as not to put bending strain on the pressure pot therefore if this pressure is applied as shown only a part of 15 the pot is strained during locking and this strain is one of compression. On the other hand, in the preferred method of refilling the pressure pot it is necessary to have these locking means out of the way when the 20 vacuum bell 72 is lowered. If a tilting pressure pot is used a double support need not be used inasmuch as the locking could be accomplished by pressure on the bars 27 and the back and front of pressure pot 26 25 could be connected by a rib or web. Such a pot could be tilted by extending down the link 73 and utilizing the power of the lever 74 to tilt the pot, although, of course, other forms of tilting means might well be 30 used.

Simultaneously with the operation of the pressure pot as described, the die members are brought together and separated, in accordance with the movement of the pressure pot, by the power applied by the prime mover through a cross-head 56, associated with the rods 21, carrying the ejector-die section, and the piston 46, to which the connecting rod 45 is secured. The cross-head 40 56 is carried by the four rods 21 at the rear end of the machine, and is clamped upon said rods by nuts 57 threaded upon the rods, so that the cross-head is adjustable longitudinally thereof. The central portion 45 of the cross-head 56 is provided with a cylindrical chamber 58 in which is positioned the piston 46, and the cross-head 56 to permit of slight lost motion. This lost motion while hereinafter more fully described, 50 is for the purpose of allowing of the breaking of the sprue before the die is opened to obviate fractures of the casting due to the breaking of the sprue.

It will thus appear that the prime mover, 55 operating through the connecting rod 45 serves, not only to move the pressure pot into and out of casting position, but, simultaneously serves to slide the rods 21 longitudinally of the machine for the purpose of 60 opening and closing the die.

In carrying out the present invention commercially, the nozzle 32 of the pressure pot may be brought into direct engagement with the sprue-die section 9 to introduce 65 metal directly from the nozzle into the die,

but, in the preferred embodiment of the invention, the machine is preferably provided with an intermediate portion 59 which is supported by the fixed plate 5 for longitudinal sliding movement relative thereto. 70 The preferred construction of this intermediate member is shown in Figures 14 and 15. It is built up of two coaxial tubular elements or sleeves 59^a and 59^b threaded together and which sleeves are channelled interiorly and exteriorly, respectively, to provide an annular chamber through which water or some other cooling medium is circulated through the inlet and outlet pipes 17^a and 18^a, all as clearly shown in Figures 8, 75 9, 14 and 15. The water jacket is thus formed which positively precludes the intermediate member from overheating. The intermediate member is provided with a seat 60 adapted to seat in a depression in 80 the sprue-die 9, and is in turn provided with an interior seat 61, adapted to receive a seat 62 on the nozzle of the pressure pot. Moreover, said intermediate member has a bell-shaped mouth 63 with which is adapted to co-operate ribs 64, formed on the pressure pot. When the pressure pot is brought into casting position, the ribs 64 are adapted to engage with the bell-mouth 63 before the nozzle enters the passage in the intermediate 85 member leading into the die opening, and serves to guide the nozzle 62 to its seat on the seat 61.

As stated, the intermediate member is mounted in the plate 5 for longitudinal movement and this movement is imparted to said member by a lever 65. The lever 65 is mounted on a pivot 66 supported on brackets 67, formed on the back plate 5. One arm of the lever 65 extends downwardly and is bifurcated to straddle the intermediate member 59 and engage the trunnions 68, formed on the intermediate member. The other arm of lever 65 extends upwardly and is connected by a link 70 to a 105 pneumatically controlled piston 71. At the conclusion of the casting operation, and while the sprue is still secured to the die, the piston 71 is pneumatically operated to impart, through the lever 65, a backward 110 kick to the intermediate member 59, for the purpose of breaking the sprue, and the parts of the machine are so associated that this breaking of the sprue will take place before the die starts to open. In this connection, 115 it will be noted that inlet passage 33 in the sprue-die section is tapered outwardly, and the outlet of the intermediate member 59 is similarly formed, so that the sprue is formed with a weakened zone at which it is broken when the intermediate member is given the sudden kick by the lever 65 as described.

A further advantage of making the sprue-die inlet tapered is that when the metal therein partially solidifies, preliminary to 130

the breaking of the sprue, the force of the kick referred to will be transmitted to the tapering wall of the inlet 33 which will take the force of the blow and will not transmit such force to the casting within the die.

The pressure pot 26 has been described as movable into and out of casting position, the reason for moving it out of casting position being to allow of the refilling or recharging thereof. In practice, the pot 26 may be filled in various ways, and its construction may be varied from that disclosed in the drawings, so that it may be tilted below the surface of the molten metal pool in which it is partially submerged to allow of the filling thereof, or may otherwise be filled. However, the method of filling the pot, 26 is preferably that disclosed in my co-pending application Serial No. 280,935, filed March 6, 1919. In this co-pending application, the preferred method of filling the pot is specifically shown and described, but in the present case, the mechanism for operating the filling mechanism is shown as co-ordinating with the remaining operating parts of the machine.

Supported for vertical movement in the machine is a vacuum bell 72 which is supported by a link 73 from a lever 74. The lever 74 is fulcrumed at 75, and with its short arm is associated a roller 76 adapted to engage with a depending flange of a cam plate 77, fixed on the crank shaft 42. The parts of the machine are so associated and timed that when the cam shaft moves to a position to retract the pressure pot into the filling position of Figure 9, the low face of the cam 77 comes into operative relation with the lever 74 and causes the vacuum bell 72 to be lowered from the position shown in Figure 8 to that of Figure 9. Timed with this operation air is exhausted from the bell 72 through the connection 78, and the pressure pot is charged as described in my co-pending application. After the pot has been charged, the bell is again lifted by the cam 77 to the position of Figure 8, and the pressure pot moved forward into casting position. Thereafter, compressed air is introduced into the pressure pot through the compressed air inlet 80, and serves to force the metal within the pressure pot into the die in the usual manner.

The consecutive steps in the operation of the machine will now be described, it being assumed that the parts of the machine are in the casting position as shown in Figures 1, 2, 3, 4, 8, 14 and 15. Fluid under pressure is admitted by a suitable valve, to one of the cylinders 37 behind the piston 38. The prime moving rack 40 actuates the gear 44, which, through the crank 43, exerts a pull on the connecting rod 45. The piston 46 moves forward for its lost motion in the

cylindrical chamber 58, and carries therewith the head 47, which, through the racks 49, gears 52 and 54, and the racks 35 are connected with the hanger 24. Simultaneously with the start of this operation for retracting the pressure pot, compressed air is admitted behind the piston 71 which operates through link 70 and lever 65 to give a backward kick to the intermediate member 59 and break the sprue. By the time the sprue is broken the lost motion of the cylinder 46 in cross-head 56 is taken up, and said piston 46 causes movement of the cross-head 56, which being secured to the rods 21, causes forward sliding movement thereof. As the rods 21 move forwardly, they carry with them the ejector die supporting plate 24, on which the ejector die section is supported, and thus serve to separate the die sections. The pressure pot is thus withdrawn to its retracted position and the die opened.

As the die approaches its full opening, the pressure pot comes into the fully retracted position of Figure 9, at which time the mutilated gears 54, which co-operate with the racks 35, come to the smooth section of the gears, and further movement of the pot ceases while the die continues to open. As soon as the pressure pot stops, the cam 77 is timed to drop the vacuum bell 72 over the mouth of the pressure pot, as shown in Figure 9, and the charging of the pot commences. The die continues to open for a short distance and reaches its maximum opening, at this time the ejector mechanism is operated and the casting is removed from the die. Fluid under pressure is now admitted to the other cylinder 37 behind the piston 39 and the die starts to close, and after it has traveled a short distance, the mutilated gears 54 once more engage with the racks 35 and start to move the pressure pot again into casting position. However, just before the pot begins to move, the cam 77 operates the lever 74 to raise the bell 72 out of the path of the pot. The pot continues to move to casting position, its nozzle being finally guided into the intermediate member 59 by the ribs 64 (Figures 14 and 15), and the ejector-die section 19 is simultaneously moved to face abutting relation with the sprue-die section. As soon as the parts become tightly associated for casting, pressure is admitted to the pot, and the molten metal therein is forced into the die, and the cycle of operations as described are recommended for the next casting.

Having thus fully described the invention, what I claim as new, and desire to secure by Letters Patent is:

1. In a die casting machine, a sprue-die supporting plate, an ejector-die supporting plate, and operating means for effecting relative movement between said plates, said

sprue-die supporting plate being positioned between the ejector-die supporting plate and said operating means.

5 2. In a die casting machine, a fixed sprue-die supporting plate, a movable ejector-die supporting plate, operating means for moving said ejector-die supporting plate to and from the sprue-die supporting plate, said sprue-die supporting plate being positioned 10 intermediate the ejector-die supporting plate and said operating means.

15 3. In a die casting machine, a sprue-die supporting plate, an ejector-die supporting plate, and fluid pressure operating means for effecting relative movement between said plates, said sprue-die supporting plate being positioned between the ejector-die supporting plate and said fluid pressure operating means.

20 4. In a die casting machine, a sprue-die supporting plate, an ejector-die supporting plate, operating means for effecting relative movement between said plates, said sprue-die supporting plate being positioned between the ejector-die supporting plate and said operating means, and means for cooling the sprue-die supporting plate.

25 5. In a die casting machine, a fixed sprue-die supporting plate, an ejector-die supporting plate movable relative to the fixed plate, and positioned at one side of said fixed plate, and operating mechanism at the other side of the fixed plate for moving the movable plate to and from the fixed plate.

30 6. In a die casting machine, a fixed die supporting plate, a relatively movable die supporting plate, guides for mounting the movable die supporting plate for movement to and from the fixed die supporting plate, and means co-operating with said guides for imparting movement to the movable plate, which means are located on one side of the fixed die supporting plate, while the movable plate is located on the opposite side of the fixed plate.

35 7. In a die casting machine, relatively movable die supporting plates, a pressure pot movable to and from one of the die supporting plates, and common means for effecting relative movement in alternately opposite directions between the die supporting plates and between at least one of the die supporting plates and the pressure pot, while the plates and pot are maintained in substantially horizontal alinement.

40 8. In a die casting machine, a fixed sprue-die supporting plate movable relative thereto, a pressure pot movable to and from the fixed sprue-die supporting plate, and unitary means for effecting the movement of the movable die supporting plate and the pressure pot in alternately opposite directions, while the plate and pot are maintained in substantially horizontal alinement.

45 9. In a die casting machine, a movable

ejector-die supporting plate, a pressure pot, a prime mover, connections between the prime mover and the movable ejector-die supporting plate for positively moving said plate in a horizontal direction, and connections between the prime mover and the pressure pot for yieldably forcing the pressure pot in a horizontal direction into casting position, the supporting plate and pressure pot being alternately moved in opposite directions and in substantially horizontal alinement.

50 10. In a die casting machine, relatively movable die supporting plates, complementary sections carried by said plates, a pressure pot bodily movable relative to both of said plates in a horizontal direction, and means for rigidly bringing the die sections into casting relation, and for yieldably forcing the pressure pot into casting position relative to the die.

55 11. In a die casting machine, relatively movable die supporting plates through one of which a metal conduit passes, a pressure pot movable relative to one of said plates, means for charging the pressure pot, and common means for effecting relative movement between the die supporting plates and for operating the means for charging the pressure pot and to alternately move said pot into and out of cooperative relation with the metal conduit.

60 12. In a die casting machine, relatively movable die supporting plates through one of which a metal conduit passes, a pressure pot movable relative to one of said plates, means for charging the pressure pot, and automatic means for effecting relative movement between the die supporting plates and for operating the means for charging the pressure pot and to alternately move said pot into and out of cooperative relation with the metal conduit.

65 13. In a die casting machine, relatively movable die supporting plates, a pressure pot movable relative to one of said plates, means for charging the pressure pot, and fluid pressure means for effecting relative movement between the die supporting plates and for operating the means for charging the pressure pot and to move said pot into a position to feed metal into the die through a passage in one of the supporting plates provided for this purpose.

70 14. In a die casting machine, relatively movable die supporting plates, a pressure pot suspended for bodily reciprocation in a horizontal direction relative to both of said plates, means for charging the pressure pot, means for effecting the relative movement between the die supporting plates, and means for moving the pressure pot to bring the latter into position to feed metal to the die through a metal conduit, provided for this purpose, on one of the plates, in combi- 120

- nation with unitary means for controlling the operation of the moving and charging means.
15. In a die casting machine, a pressure pot having a nozzle portion provided with a valve seat and a part of which nozzle portion projects beyond the valve seat, a sprue-die section provided with a valve seat, a member intermediate said nozzle and the sprue-die section, said intermediate member being adapted to be seated in the valve seat of the sprue-die section and being provided with a seat to receive said nozzle seat.
16. In a die casting machine, a pressure pot provided with a nozzle, having a seat and a part projecting in front of said seat, a sprue die section provided with a seat, an intermediate section adapted to engage with the seat of the sprue die section and form a seat for the nozzle, and means for cooling said intermediate section.
17. In a die casting machine, a die, a pressure pot provided with a nozzle, an intermediate portion through which the metal is fed from the nozzle to the die when the parts are in casting position, and means for imparting a sharp knock to said intermediate portion to move it away from the die for the purpose of breaking the sprue.
18. In a die casting machine, a die, a pressure pot provided with a nozzle, an intermediate portion through which the metal is fed from the nozzle to the die when the parts are in casting position, and means for imparting a sharp knock to said intermediate portion to move it away from the die for the purpose of breaking the sprue, and simultaneously retracting the nozzle from its casting position.
19. In a die casting machine, a die provided with a sprue passage, a pressure pot provided with a nozzle, and an intermediate member positioned between the nozzle and the die and having a passage through which metal flows from the pressure pot into the die, the passages of the intermediate member and the die being tapered in opposite directions to provide a line of weakness at the point where the said two passages meet, for the purpose of allowing the sprue to be more readily broken from the die.
20. In a die casting machine, a die having a sprue opening, the area of the inlet of which is less than that of the outlet, a pressure pot provided with a nozzle, a feed member intermediate the nozzle and the said sprue opening, said feed member having an outlet of substantially the same area as the inlet to the sprue opening, whereby the sprue having a weakened section is formed on the casting.
21. In a die casting machine, a die provided with an inlet, a pressure pot provided with a nozzle, an intermediate member having a passage for feeding metal to the inlet of the die, and means mounted on the pressure pot and co-operating with the intermediate portion for guiding the nozzle into the passage of the intermediate portion, said means operating so as to engage with the intermediate member before the nozzle enters the passage of the latter.
22. In a die casting machine, a die supporting plate, a die mounted on one side of said plate, a source of metal supply on the opposite side of said plate, a member intermediate the source of metal supply and the die, and common means for cooling the die supporting plate and the said intermediate member.
23. In a die casting machine, a die embodying separable sections, one of which is fixedly mounted and the other of which is movable toward and away from the fixed die section, a receptacle adapted to contain a pool of molten metal, a pressure pot adapted to be suspended from the metal in said receptacle and mounted for sliding movement toward and away from the fixed die section, and means for forcing the die sections together and for yieldably forcing the pressure pot into cooperative relation with the fixed die section.
24. In a die casting machine, a sprue die supporting plate, an ejector die supporting plate operating means for effecting relative movement between said plates, and a movable pressure pot, the said sprue die supporting plate being positioned between the ejector-die supporting plate and said operating means.
25. In a die casting machine, a die, in combination with means for breaking the sprue through a direct pull in a direction longitudinal of the sprue, without opening the die and without moving said die from the casting position.
26. A die supporting plate for casting machines embodying a substantially central channel into which a cooling fluid is introduced, laterally extending channels leading from the central channel toward the lateral edges of the plate, and means for allowing of the egress of the cooling fluid after it has traversed said channels.

In testimony whereof, I have signed my name to this specification.

CHARLES M. GREY.
